UNITED STATES PATENT OFFICE.

JABEZ T. WARREN, OF LE ROY, NEW YORK.

HORSE-POWER.

SPECIFICATION forming part of Letters Patent No. 240,480, dated April 19, 1881.

Application filed March 22, 1881. (No model.)

To all whom it may concern:

Be it known that I, JABEZ T. WARREN, of Le Roy, in the county of Genesee and State of New York, have invented certain new and 5 useful Improvements in Horse-Powers, of which the following is a specification.

In Letters Patent No. 228,576, granted to me June 8, 1880, a horse-power is shown similar in general construction to that herein described; and my present invention consists in certain improvements on that class of machines, as will hereinafter be set forth.

In the accompanying drawings, Figure 1 is a perspective view of my improved machine; 15 Fig. 2, a sectional view on the line 2 2 of Fig. 3; Fig. 3, a vertical section on the line 3 3 of Fig. 2; Fig. 4, a detached view, partly in section, showing the manner of driving the planet-wheels and of attaching the sweep to the 20 top plate of the machine; and Figs. 5 and 6 are detail views of the knuckle or tumbling rod connection.

The casing of the horse-power, which consists of a drum or barrel, A, and two end plates, a a', securely united by bolts B, is fastened to a frame or bed-plate, X. A vertical shaft, C, turning in bearings in the plates a a', carries a large bevel-wheel, D, within the drum and a pinion, E, near its upper end, 30 above the plate a. The bevel D gears with a bevel-pinion, d, upon the power-transmitting shaft H, which has its bearings in the casing. The shaft C is driven by the planet-wheels F F, which gear with the pinion E and the internally-geared ring G, which, in this instance, 35 is shown as made in one piece with the plate a. The top plate, I, to which the sweep K is attached, turns upon the shaft C.

Thus far the construction of the machine is 40 the same as that shown and described in my patent above mentioned. In that patent, however, the planet-wheels are shown as driven by a round pin or lug on the top plate, which enters a corresponding socket in the wheel. 45 In the present case the wheels are provided with a central hub or trunnion, f, having an annular depression or recess, f', around it. The trunnion f has its bearing between two lugs, i i, on the top plate, the outer sides of 50 which are curved to conform to the recess f', and their bearing-faces next the trunnion

straight, to present a small surface of contact. By this construction the machine can be run equally well in either direction, friction and wear are very much reduced, and constant oiling is not necessary, as the annular recess retains the oil. Of course a single lug or bearing only for the trunnion of each planet-wheel may be employed, and the machine will work perfectly well in one direction; but where it 60 is desired to have it run in both directions I use two lugs or bearings, as above described. Two planet-wheels are shown, but obviously a single wheel may be used, or more than two.

I attach the sweep K to the top plate, I, so 65 that it can be adjusted in height to suit horses of different sizes, and in length to suit the floor or space in which the machine is working. A lug, c, having an eye therein, is formed upon the top plate, to one side of the shaft C. Directly in front and rear of this lug are rests or sockets M M', of different heights, for the sweep, which rests are cast or otherwise formed on the top plate. Two such lugs and pairs of rests are shown for the attachment of two sweeps 70 to the machine. The sweep is secured in place by a right-angle bolt, k, and nut k', the bent end of the bolt entering the eye in the lug c and its long arm passing through the sweep. The bottoms of the rests are beveled in the 75 same plane, so as to give to the sweep a firm support. The sweep is adjusted in height by interposing a plate or plates, N, between it and the rests—the higher or the lower one, according as it is desired to elevate or depress its 80 outer end to suit the height of the horse. Bolt-holes k², of which there may be any suitable number, are made in the sweep, so that it can be adjusted in length for the purpose above mentioned.

The draft devices are similar in principle to those shown in my patent before mentioned, where the horse faces the sweep, the whiffle or evener being in front of him. My present invention contemplates an improvement upon 95 the construction therein shown. The shafts O O are rigidly attached to the sweep, and the draft-bars P P slide and rest upon them, their movement being guided and limited by pins o on the shafts which enter slots p in the draft-bars. The draft-bars pass over or through the sweep and are pivoted to the evener Q, which 90 100

is pivoted to the draft-hook *q*. By this construction I attain great cheapness, simplicity, and durability. The power is transmitted from the shaft *H* to the tumbling-rod *R* by a flexing 5 knuckle or joint, *S*. This joint consists of a socket, *s*, in the socket-opening *s'* of which the head *r*, which fits loosely on the squared end of the tumbling-rod *R*, works. The portion *s²* of the socket *s* fits loosely on the squared end 10 of the shaft *H*, so as to revolve with it. The parts are prevented from separating by a collar, *T'*, at the outer bearing, *T*, of the tumbling-rod. The head *r* is square in transverse section, as shown in Fig. 6, and is rounded in 15 longitudinal section, as shown in Fig. 3. The socket-opening *s'* is square in cross-section to fit the head *r*, and its inner end is curved to correspond with the curve of the head. The head and its socket, instead of being square in 20 cross-section, may be of any other angular shape. By this construction the tumbling-rod is free to flex, and can be driven at any desired angle within certain limits. The joint is very 25 efficient, can be cheaply made, and readily put together. I also dispense with the danger as well as the expense and trouble incident to joints where knuckle-pins are used.

The improvements above described are, of course, applicable to many machines differing 30 somewhat in construction from that herein shown.

Having thus described my invention, what I claim as new, and desire to secure by Letters Patent, is—

35 1. The combination of the planet-wheel, having the trunnion and annular recess, as set forth, of the top plate, and the lug or lugs which form the bearing of the trunnion, substantially as described.

2. The combination of the top plate, the 40 sweep, rests or sockets for the sweep, mechanism for securing the sweep in place, and removable plates for regulating the height of the sweep, substantially as described.

3. The combination of the top plate, the lug 45 and bolt for securing the sweep to the plate, a rest or socket on each side of the lug, the rests being of different heights, and removable plates for regulating the height of the sweep, substantially as described.

4. The combination of the sweep having a series of bolt-holes therein, the top plate, rests for the sweep, and a bolt for securing the sweep in place, whereby the sweep can be adjusted in length, substantially as and for the purpose 50 set forth.

5. The combination of the sweep, the shafts attached thereto, the pins on the shafts, the slotted draft-rods which rest and slide on the shafts, and the evener, substantially as de- 60 scribed.

6. The combination of the shafts *H* and *R* with the knuckle or flexing joint, herein described, for transmitting power, consisting of a head which is angular or square in cross-section and rounded in longitudinal section, and a socket angular or square in cross-section, in which the head works, substantially as set forth.

7. The combination, substantially as de- 70 scribed, of the shafts *H* and *R*, the socket *s*, having the socket-opening *s'*, and the head *r*.

In testimony whereof I have hereunto subscribed my name.

JABEZ T. WARREN.
